CLAIM

I claim the ornamental design for a plate-type handicraft gauge, as shown.

DESCRIPTION

FIG. 1 is a front view showing a plate-type handicraft gauge according to a first embodiment of my design, a rear view being symmetrical to the front view;

FIG. 2 is a top plan view of the same which is identical to a bottom view;

FIG. 3 is a right side view of the same which is identical to a left side view; and,

FIG. 4 is a sectional view of the same taken along lines 4-4 in FIG. 1.
